UNITED STATES PATENT OFFICE.

JOHN MICHALEK, OF CHICAGO, ILLINOIS.

LOCK.

1,416,855.

Specification of Letters Patent. Patented May 23, 1922.

Application filed April 22, 1921. Serial No. 463,437.

To all whom it may concern:

Be it known that I, JOHN MICHALEK, a citizen of the United States, and a resident of the city of Chicago, county of Cook, and State of Illinois, have invented certain new and useful Improvements in Locks, of which the following is a specification.

My invention relates to improvements in locks and more particularly to combination locks, and has for its object the provision of a keyless lock operated by a stem and a combination of numbered disks which may be readily set for various combinations.

Other objects will appear hereinafter.

The invention consists in the combinations and arrangements of parts hereinafter described and claimed.

The invention will be best understood by reference to the accompanying drawings forming a part of this specification, and in which,

Fig. 1 is a partial sectional view of a door showing my lock applied thereto;

Fig. 2 is a view of the entire lock;

Fig. 3 is a sectional view on line 3—3 of Fig. 2;

Fig. 4 is a sectional view on line 4—4 of Fig. 3;

Fig. 5 is a sectional view on line 5—5 of Fig. 3;

Fig. 6 is a detail view of the inner disks;

Fig. 7 is a detail view of the numbered outer disks; and,

Fig. 8 is an inverted plan view of the lowest outer or numbered disk.

My invention illustrated comprises a casing 10 having a cover plate 11 from which extends a bushing 12. Lugs 13 extend inward from the casing walls to retain the cover plate in position. A bolt 14 extends through an opening in the front wall of the casing and is normally forced outward by a spring 15 which bears on the bolt and on the wall of the casing and is coiled around a pin 16 mounted in said casing and extending through an opening in the cover plate 11, as shown in Fig. 2. A lug 17 extends upward from the middle portion of the bolt and a slot 18 is provided at the inner end of said bolt.

The combination of the lock comprises a series or plurality of marked or numbered outer disks, and a companion series of cooperating inner disks, the number of outer disks being equal to the number of inner disks. Each outer disk carries a series of

equally spaced marks or numbers as shown in the drawings. Any number of pairs of companion disks may be used.

In the form illustrated the series of disks 60 consists of three outer and three inner disks. The lower outer disk 20 bears a plurality of equally spaced marks or numbers on an upper bevelled edge 21 and is provided with an integral sleeve 22 having depending lugs 65 23 which fit and engage in the notches 24 of the sleeve 25 of a companion inner disk 26 rotatable by said outer disk 20. Said disk 26 is provided with a slot 27 (see Figs. 4 and 6) and notches 28 extending laterally from 70 said slot which are adapted to receive the lug 17 of bolt 14 and form projecting portions or means on said disk to lock said bolt in withdrawn position. An intermediate disk 30 bears numbers on its upper bevelled edge 75 31, spaced in accordance with those on disk 20 and so arranged as to be placeable immediately above the numbers on said disk 20. Said disk 30 is provided with an integral sleeve 32 fitting in sleeve 22 and having depending lugs 33 which engage in notches 34 of sleeve 35 of a companion disk 36 which is provided with a slot 37 similar to slot 27 on disk 26, said sleeve 35 fitting within sleeve 25. An upper disk 40, bearing on a 80 bevelled edge 41, numbers spaced and positioned similarly to those on disks 20 and 30, is provided with a sleeve 42 having depending lugs 43 which engage in notches 44 in a sleeve 45 of a companion disk 46 provided 90 with a slot 47 similar to slots 27 and 37. A stem 49 is provided with an upper knob 50 and lower angular portion 51 which engages in an angular opening 52 of an arm or follower 53 which engages in slot 18 in lock 95 bolt 14 for moving said bolt. A threaded member 54 is fastened to the inner end of said stem to hold it in position in the sleeves and to hold the disks assembled (see Fig. 3), and a groove or index 55 is provided on the 100 edge of knob 50.

In assembling and setting the lock for a certain or predetermined combination the bolt 14 and arm 53 are placed in position as shown in Fig. 5, the disks 26, 36 and 46 are 105 placed together with their slots 27, 37 and 47 in register and in line to receive lug 17 of bolt 14, as shown in Fig. 4, the cover plate is added and clamped in position by the side walls of the lock, the numbered 110 disks are then placed together and inserted in neck 12 of the plate. The numbers on

the outer disks may be set in various predetermined positions forming various combinations. In the form illustrated the companion disks are provided with two lugs and 5 notches and in view thereof each outer disk may be set in two distinct positions, at 180° apart. The number of these settings or arrangements may be increased by increasing the number of slots on the inner sleeves, and 10 the number of combinations may be further increased by increasing the number of pairs of disks. The stem is placed through the sleeves and fastened in position by means of member 54 to hold the members together, 15 the groove 55 on knob 50 extending forward toward lug 17 and in alignment with the registering slots of the inner disks. The stem and disks may be set in position shown in Fig. 2, placing numbers 7, 14 and 17 over 20 the aligned slots extending forward along the center line of bolt 14, to form the combination with which the stem may be turned and through its arm 53 be enabled to withdraw the bolt by sliding lug 17 in the 25 aligned slots. The bolt may also be locked open by turning the numbered disk 20 and through its lugs the companion inner disk 26, bringing lug 17 into one of the notches 28 extending laterally from the slot 27. 30 When the bolt is not locked in withdrawn position the spring 15 will normally extend the bolt and hold it in extended or shot position. The angular opening 52 in the arm and the angular portion 51 on the stem are 35 made irregular in order that the stem will only fit in said opening in a definite position so that the notch 55 on the knob of the stem will extend in the direction of the longitudinal portion of the arm 53. This is done in 40 order that the stem may be introduced in the arm only in the correct position enabling it to withdraw the bolt when the slots on the disk are in aligned forward position.

The lock is mounted on the article or container to be locked, as for instance a door 45 56 as shown in Fig. 1, with the bushing 12 and the numbered disks extending to the exterior through the wall of the article or container, making the numbered disks and knob 50 of the stem readily accessible to be operated. The lock is well adapted for use on doors, safes, ice-boxes, trunks, tool chests, and various other articles, and may be made with 55 any plural number of pairs of companion disks and in any desired shape and size.

While I have illustrated and described the preferred form of construction for carrying my invention into effect, this is capable of variation and modification without departing 60 from the spirit of the invention. I, therefore, do not wish to be limited to the

precise details of the construction set forth, but desire to avail myself of such variations and modifications as come within the scope of the appended claims.

65

Having described my invention, what I claim as new and desire to secure by Letters Patent, is:—

1. A combination lock comprising a series of outer disks; a series of inner slotted disks; means on each outer disk to engage and rotate one of said slotted disks; a bolt lockable in extended position; means on said bolt adapted to slide in said slots; means engaging said bolt to withdraw the same when said slots are in predetermined alignment; and means on said disks co-operating with said means on said bolt to lock said bolt in withdrawn position.

70

2. A combination lock comprising a series of outer marked disks; a series of inner slotted disks engaged and rotated by said marked disks; a bolt in said lock; means on said bolt adapted to slide in said slots; means to automatically move said bolt to extended position; means to lock said bolt in extended position; and a notch extending from the slot in one of said disks for receiving the means on said bolt to retain said bolt in withdrawn position.

75

3. A combination lock comprising a series of outer numbered disks; a series of inner slotted disks; means on each numbered disk to engage and move one of said slotted disks, one of said slotted disks being provided with a notch; a bolt on said lock and a lug on said bolt adapted to slide in said slots during withdrawal of said bolt and engage said notch to retain said bolt in withdrawn position.

80

4. A combination lock comprising a series of outer marked disks; a series of inner slotted disks; means on each marked disk to engage and rotate one of said slotted disks and bring said slots in alignment by rotating said marked disks in the same direction; a bolt in said lock; means extending from said bolt adapted to slide in the aligned slots and permit movement of said bolt; resilient means to normally force and retain said bolt in extended position; and a notched portion on one of said disks to engage said means on said bolt to hold said bolt withdrawn by turning said disk.

100

In testimony whereof I have signed my name to this specification in the presence of two subscribing witnesses.
